[57] CLAIM

The ornamental design for a shoulder bag, as shown and described.

DESCRIPTION

FIG. 1 is a perspective view of a shoulder bag showing my new design as worn on a user's shoulder;
FIG. 2 an alternate perspective view thereof showing the bag off a shoulder; and,
FIG. 3 is a sectional view taken on line 3—3 of FIG. 1. The broken line showing of a person in FIG. 1 is for illustrative purposes only and forms no part of the claimed design.
